(57) **CLAIM**

The ornamental design for a reversible rake, as shown and described.

DESCRIPTION

FIG. 1 illustrates an isometric top view of a reversible rake showing my new design;

FIG. 2 illustrates a top view thereof;

FIG. 3 illustrates a bottom side view thereof;

FIG. 4 illustrates a left side view thereof;

FIG. 5 illustrates a right side view thereof;

FIG. 6 illustrates a front view thereof; and,

FIG. 7 illustrates a rear view thereof.

The handle of the rake is shown with a symbolic break. Any portions shown between the break lines form no part of the claimed design.
